HAIR WAVER

Louis V. Bregou, Worcester, and Philip E. Berling, Auburn, Mass.; said Berling assignor to said Bregou, Worcester, Mass.

Application November 5, 1936, Serial No. 109,364

18 Claims. (Cl. 132—33)

This invention relates to a hand device for waving locks of hair.

The principal objects of this invention are to provide a waver having jaws which can be opened to receive the hair by the reciprocation of a bar; to provide means for holding the bar in a position for holding open the jaws of the waver while the wave of hair is secured by a wire; to provide a magazine in the waver for pieces of wire constituting an improved form of hairpin, which wires will pass into the hair about twice the width of the lock of hair and can then be bent over by hand to hold the hair in position; to provide a feeder bar therefor operated in a convenient manner; to provide a pusher rod located on the jaw opener rod and operated by hand to push one of the wires forward; to provide a magazine with a slot for receiving the wires; to provide the feeder bar with means for feeding the wires around through a groove to a point from which they are to be pushed into and through the hair on the waver jaws, said operation being circumferential; and to provide other features for the efficient operation of a waver, whereby the operation of sterilizing the hairpins, after they are manufactured, will be eliminated owing to the fact that they are never used a second time.

Other objects and advantages of the invention will appear hereinafter.

Reference is to be had to the accompanying drawings in which

Fig. 1 is a full-sized plan of the entire instrument with the jaws in closed position;

Fig. 2 is a similar view of the main casing of the same separated from the other part of the casing;

Fig. 3 is an end view thereof;

Fig. 4 is a view of the left-hand part of the casing separated from the right-hand part;

Fig. 5 is a view of the interior parts of the device with the outer casing removed to show interior construction;

Fig. 6 is a side view of the feeder bar;

Fig. 7 is a sectional view of the same on the line 7—7 of Fig. 6;

Fig. 8 is an end view of the collar;

Fig. 9 is a side view of the magazine with parts connected therewith;

Fig. 10 is a longitudinal section of the core shell and other internal parts;

Fig. 11 is a side elevation of the jaw opener rod;

Fig. 12 is a longitudinal central sectional view

of the magazine and connected parts at one end;

Fig. 13 is a sectional view of the jaws on the line 13—13 of Fig. 12;

Fig. 14 is a sectional view on the line 14—14 of Fig. 12 showing the magazine empty;

Fig. 15 is a transverse sectional view of the wire magazine and associated parts showing the wires in the magazine;

Fig. 16 is a longitudinal central sectional view of the magazine showing the feeder bar and pusher collar and intermediate parts;

Fig. 17 is a longitudinal central sectional view of the parts between the pusher and the opposite end of the jaw opener rod;

Fig. 18 is a sectional view on the line 18—18 of Fig. 17;

Fig. 19 is a side view of the outer casing of the magazine with most of the parts shown in section and the jaws open;

Fig. 20 is a view similar to the left-hand end of Fig. 19, showing the jaws open and covered with a lock of hair;

Fig. 21 is a view similar to Fig. 19 with the jaws closed;

Fig. 22 is a view of the end of the device with the jaws closed and the hairpin also closed over the hair, and

Fig. 23 is a sectional view of a modified form of jaws.

This is a type of hair-curling device in which the instrument involves a pair of cylinders 10 and 11 which are connected together and which constitute the handle of the device and the means for supporting the jaws and operating devices inside this double cylinder.

The cylinder 11 is provided with a circumferential slot 12 through which extends the neck of a screw-head 13 into a collar 14 inside the cylinder. Thus the collar can be turned on its axis, guided by the slot 12. To this collar 14 is fixed a feeder bar 15 by a screw and to the end of the feeder bar is fixed a collar 16.

The collars 14 and 16 are concentric and secured together by the feeder bar 15. This construction is turned by the head 13 in the slot 12. On the back of the collar 14 is a hollow collar 17 fixed to a sleeve or core shell 18 by a screw 19. This collar 17 is provided with a coil spring 20 inside fixed to the end of the collar 17 at one end and to the collar 14 at the other. In this way the feeder bar 15, which is supported between the two collars 14 and 16, can be turned around on a magazine 21 and this action resisted by the spring 20. The annular magazine 21 is 55

provided to hold on the outside thereof longitudinal wires 22 which are to be fed forward around the magazine to be used as hairpins. It has a curved external slot 23 for receiving such wires, circumferential at its inlet side and extending spirally toward the center at its outlet. The feeder bar 15 is in this cylinder 11 and constitutes a wire pusher, and is moved circumferentially in the cylinder to feed the wires ahead 10 of it sideways.

Projecting radially through a longitudinal slot 24 in the end of the casing 10 is a head 25, having a neck inside the cylinder by which it is connected with a pusher collar 26 inside the casing. 15 It will be seen that this head can be moved longitudinally the length of the slot 24, which acts as its guide. This results in moving a wire 22 longitudinally out of the magazine.

A jaw opener rod 30 is provided having a slot 20 27 from which slot projects a radial end 28 of a longitudinal pusher rod 29, which is seated in the slot 18a extending under the shell 18. The moving of the head 25 also moves with it positively the pusher rod 29 in the slot 27 into the 25 inner end of the magazine where a wire is located, as shown in Figs. 14 and 15. A spring 33 is located between a collar 34, fixed to the sleeve or core shell 18, and a collar 35 which is slidable on the sleeve 18 through a slot and pin 6. The 30 pusher rod 29 at its left end engages the end of one wire located at the end of its magazine and pushes it out, as shown in Figs. 17 and 22.

The magazine is shown as having an external surface of nearly a circle and a spiral, the spiral 35 coming inwardly toward the center and terminating at the point at which the rod 29 is located on the side of the sleeve or core shell. This configuration just described is in the solid magazine. The feeder bar 15 is turned from one position on the cylindrical part of the magazine to another by oscillation with its two rings. The magazine is filled with wires through a slot 23, as stated. They are fed sidewise and used only once.

The jaw opener rod 30 is provided at its left-hand end with a conical recess 36, as stated. 45 At the extreme end of the waving implement is a pivot pin 38 on which are pivoted two levers, each lever being made up of a handle and a jaw. The jaws project from the end of the main implement because the pin 38 is pivoted in the fixed sleeve 18. The jaws 39 are forced apart to form the wave and are brought together to allow the tool to be withdrawn from the wave.

When the rod 30 is pushed up to the position 55 as shown in Fig. 19, the ends of the handles of the waving iron will be pushed inwardly by the conical recess 36, and the iron will be open. When this rod 30 is moved back these jaws will be released and the spring 41 will close the jaws, as shown in Fig. 12.

At one end of the collar 17 there is a radial plunger 42 adapted to pass into a perforation 43 in the core shell 18 and into a recess 44 in the jaw opener rod 30 to stop the rod and prevent 60 its moving at the time in either direction. This plunger is forced inwardly by a spring. The plunger is provided with a cam surface 45 which is slanted at the bottom. When the rod 30 is moved to the position shown in Fig. 19 in full 70 lines to hold the jaws open, the recess 44 will register with the plunger 42 and the spring will force the plunger into the recess which will hold the two longitudinally movable parts against further longitudinal motion. This will also hold the 75 jaws 39 open. A cam 46 is adapted to move

under the bottom of this cam surface 45 to move the plunger outwardly against the force of its spring. The cam 46 is mounted on the pusher collar 26. Therefore, this pusher collar unlocks the jaw opener rod and allows the rod to be withdrawn to the position shown in Fig. 12 and the jaws 39 to close. The motion pushing in the cam 46 pushes the wire out of the magazine and into a lock of hair on the jaws 39 of the waving implement.

It will be seen by reference to the last sheet of drawings that the rod 30 is moved forward so as to close the handle ends of the iron, as shown in Fig. 19. Then the hair is placed in position over the jaws thereof and coiled around them, as shown in Fig. 20. The wire 22 is forced through, as shown in full lines in Fig. 22, and then the wire is bent back by hand, as shown in dotted lines in that figure, to hold the wave of hair.

In operation, the implement is held in one hand 20 by the casing 10 and 11. The jaws are opened by the moving jaw opener rod 30. The conical recess 36 in the end of this rod engages the handle ends of the waving levers and opens the jaws on the pivot 38. At this time, of course, the plunger 25 42 enters the recess 44 and holds the jaws open while the wave is being made. The spring 41 resists this action and, when the jaw opener rod is drawn back at the end of the operation, closes the jaws. After they are open the operator moves 30 the implement so that the jaws are in the proper position on the hair, places a finger of the other hand on the hair, and turns the whole device, by rotating the casing 10—11 by hand on its own axis, so that the hair will be coiled up on the 35 jaws. The handle 25 is operated to push inwardly the rod 29 and move it along the groove 27 into the inner end of the magazine. This results in the pushing through the magazine of the bottom pin therein and moving it through the lock of hair, as shown in Fig. 22. This is a soft wire and is bent back by hand, as shown by dotted lines in Fig. 22, to act as a hairpin to hold the hair. The action of the collar 26 which moves the wire 22 also moves the cam 46 and pulls the plunger 42 out of the recess 44 and allows the spring 33 to move the collar 35 back toward the right hand and take with it the jaw opener rod 30. This rod 30 can move only until the pin 6 gets to the end of the slot 18a in the sleeve 18. This releases the cold iron and causes the jaws 39 thereof to be closed. The jaws being closed, the cold iron can now be pulled out of the wave of hair and that wave left in the pin 22 until it is shaped by the usual drying process. Afterwards the pin is taken off and thrown away.

It is for this reason that the sterilization of the hairpins is not required, and therefore the expense of waving is very greatly reduced.

In Fig. 23 is shown a cross section of a modified form of jaws 39a in which the wire 22 is guided inside the jaws. A guide 49 inside one of the jaws engages the wire 22 to hold it firmly in position inside and prevent any chance of its catching the hair.

It will be seen that this is a simple implement for accomplishing its purposes and that it has provisions for enabling an operator to use it, even if having but comparatively little skill.

Having thus described our invention and the 70 advantages thereof, we do not wish to be limited to the details herein disclosed, otherwise than as set forth in the claims, but what we claim is:

1. As an article of manufacture, an implement for the purpose of waving hair which comprises 75

5 a cylindrical casing, a pair of waving irons pivoted at one end of the casing and projecting therefrom, a rod located in the casing and projecting from the other end to constitute an operating handle, and means whereby the pushing in of the rod will engage the waving iron to open it.

6 2. As an article of manufacture, an implement for the purpose of waving hair which comprises two cylindrical casings connected together end 10 to end, a pair of waving irons pivoted at one end of the double casing and projecting therefrom, a jaw opener rod located in the casings and projecting from the other end to constitute an operating handle, and means whereby the pushing 15 in of the rod will engage the waving iron to open it.

10 3. As an article of manufacture, a hair waving implement comprising a casing, a waving iron comprising two jaws pivoted together at one end of the casing and extending backwardly in the 20 casing, a reciprocable central jaw opening rod in the casing having means adapted to engage the handle ends of the waving iron in the casing and open the jaws when the rod is pushed in, and means for closing the jaws when the rod is moved 25 backwardly.

30 4. As an article of manufacture, a hair waving implement comprising a casing, a waving iron comprising jaws pivoted together at one end of the casing and having handle ends extending backwardly in the casing, a reciprocable central jaw opening rod in the casing having a substantially conical recess in the end adapted to engage the handle ends of the waving iron, and open the jaws when the rod is pushed in, and 35 a spring for opening the handle ends and closing the jaws when the rod is moved backwardly.

35 5. A hair waving implement comprising a casing for supporting all the parts thereof and for use in handling the implement, a pivoted double-jawed waving iron at one end with the jaws projecting from that end and the handles projecting inwardly and centrally, a rod in the casing projecting outwardly therefrom at the opposite end to constitute a handle and having means at the opposite end for engaging the handles of the waving iron and opening its jaws when it is pushed inwardly, and means for locking the rod in the position in which the iron is opened in order to hold the hair on the iron.

40 50 6. A hair waving implement comprising a casing for supporting all the parts thereof and for use in handling the implement, a pivoted double-jawed waving iron at one end with the jaws projecting from that end and the handles projecting inwardly, a rod in the casing projecting outwardly therefrom at the opposite end to constitute a handle and having means at the inner end for engaging the handles of the waving iron and opening the jaws when it is pushed inwardly, 45 and means for holding the rod in the position in which the iron is opened, and means for releasing said locking device, whereby the jaws will close so that the hair can be taken off the jaws.

45 65 7. In an implement of the class described, the combination of a casing for holding all the parts, a waving iron having jaws projecting outwardly from one end of the casing and handles projecting inwardly, a rod projecting from the other end of the casing and having a conical recess in the 50 end toward the iron for engaging the ends of the handles of the jaws to open the jaws, means for locking the rod in its opening position, said rod having a groove along one side, a wire pusher movable along said groove, and a magazine in which wires for use on the hair are adapted

to be located, the end of said magazine registering with the end of said groove.

5 8. As an implement of the class described, the combination of a casing for constituting a holder and a handle for all the parts, a waving device arranged for its jaws to project from one end of the casing, having the handles projecting inwardly, a rod in the casing, means in the end of the rod for forcing toward each other the handles of the device when the rod is pushed in to open 10 the device, said rod having a groove along one side, a wire pusher located in and movable along said groove, means for moving the pusher longitudinally in said groove, and a magazine in which wires for use on the hair are adapted to be located, the end of said magazine registering with the end of said groove, whereby the pusher rod can be moved to push the end wire in the magazine along the implement and out along the jaws, the wire being adapted to be bent upon itself to 15 hold the hair.

9. In an implement of the class described, the combination of a magazine having a transverse form comprising a large part of a circle and a spiral extending therefrom inwardly, a sleeve in 20 the center of the implement having a longitudinal groove on one side constituting the end of said magazine, said magazine being adapted to receive a plurality of wires located longitudinally, and a pusher in the groove and in registration 25 with the end wire and adapted to push that wire out of the magazine and into a position to be engaged by the hair.

10. In an implement of the class described, the combination of a magazine, a sleeve in the center 30 of the implement having a longitudinal groove on one side registering with said magazine, said magazine being adapted to receive a plurality of wires located longitudinally, and a pusher in said groove in registration with the end wire and 35 adapted to push that wire out of the magazine.

11. In a device of the character described, the combination of a magazine for receiving parallel wires having an arcuate shape with the end of it extending inwardly, a central sleeve having 40 a groove registering with the end of said magazine, a feeder bar in the magazine adapted to be oscillated therein in one direction to push the wires toward said end, a collar surrounding said sleeve, and a pusher in said groove connected 45 with said collar, said collar having a handle for pushing the pusher in the groove and thereby pushing the end wire from the magazine through the end of the device and through a lock of hair located in position for waving.

12. In a device of the character described, the combination of a magazine for receiving parallel wires having an arcuate shape with the end of it extending inwardly, a central sleeve having a groove on one side, a feeder bar in the magazine adapted to be oscillated therein in one direction to push the wires toward said end, a pusher wire in said groove and registering with the end wire in the magazine, and a collar surrounding said sleeve, said collar having a handle 55 for moving the pusher in the groove.

13. As an article of manufacture, an implement comprising a bifurcated cold iron for the purpose of shaping up hair upon it, and a movable operating rod having means at its end for opening said iron when the rod is moved toward the iron.

14. As an article of manufacture, an implement for the purpose of shaping hair, which comprises a pair of cold irons pivoted at one end 75

of the implement and having handles projecting into the implement, and an operating rod having means at the inner end thereof for engaging the handles of the iron and opening it.

15. An implement for shaping hair, comprising a pair of pivoted hair-shaping irons, a reciprocable element constituting an operating handle having means at the end for engaging the irons and turning them on their pivot to open them

16. In an implement for shaping hair, when it is moved inwardly, means for locking said element in the position in which the irons are open, and means for releasing the locking device.

17. In an implement for shaping hair, the combination of a pair of irons for shaping hair having jaws and handles, an operating handle movable longitudinally and having means for forcing together the handles of the iron and opening the jaws to put them in a position for operation, and a spring for closing the jaws when the handle is moved backwardly.

18. In an implement for shaping hair, the combination of an iron consisting of two parts pivoted together, an operating rod movable longi-

tudinally, said rod having a groove along one side, a wire pusher movable along said groove, and a transverse magazine in which wires for use on the hair are adapted to be located, the end of said magazine being located at the end of said groove.

19. An implement of the class described, comprising a cold iron composed of two parts pivoted together, an operating rod movable against the handle ends of said iron for turning the two other ends of the iron on a central axis away from each other, said operating rod having a groove thereon, a wire pusher located in and movable along said groove, and a magazine in which wires for use on the hair are adapted to be located longitudinally of the implement, the end of said magazine being located near said groove, whereby the pusher rod can be moved to push the end wire in the magazine along the implement and out along the jaws, the wire being adapted to be bent upon itself to hold the hair during the process of drying.
